UNITED STATES PATENT OFFICE

2,422,894

TRUSS PAD

Fred J. Grubb, Marshall, Mich.

Application October 1, 1946, Serial No. 700,515

3 Claims. (Cl. 128—118)

1

This invention relates to trusses.

An object of the invention is to provide a rupture pad which has a central opening surrounded by a plurality of resilient converging sector portions which move closer together to reduce the size of the opening as more and more pressure is applied thereagainst.

Another object of the invention is to provide a rupture pad which is formed of a hollow casing filled with air and which has convenient means for inflating the casing.

A further object of the invention is to provide an inflatable rupture pad which is simple in design, inexpensive to manufacture, and effective for the purpose intended.

Other objects and advantages of the invention will become apparent from the following description of a preferred embodiment thereof as illustrated in the accompanying drawings, and in which,

Figure 1 is a plan view of my improved rupture pad.

Figure 2 is a side elevation of the pad shown in Figure 1.

Figure 3 is a sectional elevation taken on line 3—3 of Figure 1, and

Figure 4 is a sectional view taken on line 4—4 of Figure 3.

Reference is now had to the drawings, in which like reference characters denote similar parts throughout the several views. As shown, there is a hollow flexible rubber casing indicated generally at 2 and having a rearward wall 4 with an air chamber 6 formed within said casing and forward of said rearward wall 4. The chamber 6 has a forward wall 8 substantially parallel to and spaced from the rearward wall 4, both walls being substantially circular in plan view with the forward wall 8 being somewhat smaller in diameter than the rearward wall. The walls 4 and 8 may also be oval or other shapes depending upon their use.

Protruding forwardly out of the casing are a plurality of inwardly curved flexible rubber fingers 10 which have air chambers 12 formed therein and communicating at their base ends 14 with the interior of the main air chamber 6. The bases 14 of the fingers 10 are thicker in cross section than their tips 16, as best shown in Figure 3, and are arcuately inwardly inclined toward the axis of the device to overlie the mouth 18 of a normally open recess 20 formed between the fingers 10 and substantially concentric with the axis of the casing 2.

A back plate 22 of metal or other suitable ma-

2

terial covers the entire back surface 24 of the casing 2, being retained in contact therewith by means of a peripheral inturned flange 26 which overlies and engages the side wall surface 28 of the casing 2 near the back surface 24 as shown.

An air valve 30 extends through aligned apertures formed in the rearward wall 4 of the casing 2 and in the back plate 22, so as to allow air to be pumped into the interior chambers 6 and 12 to inflate them to a degree depending upon the nature and size of the rupture.

The back plate 22 has an aperture 32 formed therein with a plate 34 disposed between the surface 24 of the wall 4 and the inner surface of the back plate, the plate 34 being greater in diameter than the aperture 32. The plate 34 is apertured to threadedly receive two screws 36 which also extend through apertures formed in a holding member 38 overlying the outside of the aperture 32. The member 38 has a slot or recess 40 formed in its inner surface to allow a strap or other holding member to pass therethrough for attachment to a truss belt.

It will be apparent that when the truss pad 2 is placed against the body with the mouth opening 18 over the rupture, pressure from the body against the pad 2 serves to bring the tips 16 of the fingers 10 closer together so as to more and more close the mouth 18 of the recess 20. Whenever it is desired to change the pad 2, it is only necessary to release the air through the air valve 30, take the pad 2 out of its frame and put in the new one, which is then inflated with a small air pump such as a tire pump or the like. The individual cells or hollow fingers thus fit in between and over the muscles, so that the pad will not place any pressure on the muscles, and makes for greater comfort while wearing the device.

Although I have described a preferred embodiment of my invention in specific terms, it is to be understood that various changes may be made in size, shape, material and arrangement without departing from the spirit and scope of the invention as claimed.

I claim:

1. A truss comprising a back plate, a hollow resilient air filled casing carried on said back plate, a plurality of hollow air filled resilient fingers protruding out of said casing, with their interiors communicating with the interior of said casing, said fingers being disposed about an axis substantially perpendicular to said back plate and normally spaced from each other.

2. A truss comprising a back plate, a casing

formed of resilient material and having an air chamber therein, a plurality of resilient fingers protruding forwardly out of said casing and having individual air chambers communicating with the air chamber in said casing, the tips of said fingers defining a normally open recess mouth formed therebetween, whereby pressure thereagainst will tend to reduce the size of said open mouth.

3. A truss comprising a back plate supportable on a truss belt, a casing formed of resilient material and having an air chamber therein, a plurality of resilient fingers protruding forwardly out of said casing to form a forwardly open recess therebetween, said fingers having individual air chambers communicating with said air chamber in the casing, the tips of said fingers converging toward each other to define a normally

open mouth of said recess formed therebetween, whereby pressure by the body against said finger tips will tend to reduce the size of said open mouth, and valve means for inflating and deflating said casing and fingers.

FRED J. GRUBB.
